T. W. SIMPSON

ILLUMINATED SIGN

Filed Nov. 15. 1921

INVENTOR
Tracy W. Simpson

BY
Geo. E. Townsend

ATTORNEY

UNITED STATES PATENT OFFICE.

TRACY W. SIMPSON, OF SAN FRANCISCO, CALIFORNIA, ASSIGNOR TO FEDERAL ELECTRIC COMPANY, INC., OF EMERYVILLE, CALIFORNIA, A CORPORATION OF NEW YORK.

ILLUMINATED SIGN.

Application filed November 15, 1921. Serial No. 515,192.

To all whom it may concern:

Be it known that I, TRACY W. SIMPSON, a citizen of the United States, residing at the city and county of San Francisco and State of California, have invented new and useful Improvements in Illuminated Signs, of which the following is a specification.

This invention relates to illuminated signs, and more especially to a sign of this type having removable and replaceable sign characters.

The object of the invention is to facilitate the removal and replacement of the letters whereby to change the reading matter of the same.

One form which my invention may assume is exemplified in the following description and illustrated in the accompanying drawing, in which:

Fig. 1 shows a front elevation of a sign embodying my invention.

Fig. 2 shows a sectional view taken on the line 2—2 of Fig. 1.

Fig. 3 shows a plan view in section taken on the line 3—3 of Fig. 1.

Fig. 4 shows a modified form of letter.

Referring in detail to the accompanying drawing, it will be seen that the sign comprises a box-like frame 10, on the interior of which are electric lamps 11. In front of these lamps is a glass partition 12, held in place by means of top and bottom guide lugs 13 formed upon the frame. In front of the glass partition and spaced therefrom are sign characters 14. These sign characters are preferably formed of sheet metal, with the portion constituting the letter or character cut away and formed with an inwardly extending beveled border 15. Each sign character or letter is separate from the others, and their vertical edges are overlapped as best shown in Fig. 3. The characters are held in place by means of top and bottom guide lugs 16, formed upon an overhanging portion 17 of the box-like frame. The upper guide lugs, both in the case of the glass partition and the sign characters, are somewhat elongated, and the height of the glass and sign characters is such that the latter may be inserted and removed by lifting them up to the end of the slot formed by the upper guide lugs, so that their lower edges will clear the lower guides. To fa-

cilitate lifting the sign characters I may provide each with a hand hold 18.

The glass partition is formed in sections or sheets of glass, as indicated in Fig. 3, and preferably there is some space left at either end of the frame, as indicated at 18' in Fig. 3, so that the glass sheets may be slid horizontally within their guide lugs to provide a space at any point along the length of the sign, whereby to permit access to the interior of the sign when it is desired to replace a burnt out lamp.

On account of the space between the glass and the sign character, there is no danger of breaking or displacing the glass when removing or inserting a sign character.

The present sign has a neat and attractive appearance, is simple and inexpensive to construct, and is ideally suited for theaters and other similar places where it is desired to change the reading matter on the sign at frequent intervals.

Various changes in the arrangement of the several parts herein shown and described may be employed, without departing from the spirit of my invention as disclosed in the appended claims.

I preferably arrange a clip 19 on the bottom of each sheet of glass as shown in Fig. 2, said clip being provided with a projection 20 forming a hand hold for lifting the glass, whereby to facilitate insertion or removal of the sheet.

In Fig. 4 I show a modified form of letter wherein a rib 21 is formed between the background and beveled border of the letter. This lends strength to the construction and improves the appearance thereof.

Having thus described my invention, what I claim and desire to secure by Letters Patent is:

1. An illuminated sign comprising a box-like frame fitted interiorly with lamps, sets of horizontal guides formed at the top and bottom of the frame adjacent the front thereof, a plurality of independent sign characters adapted to be received by one of said sets of guides, said sign characters being formed of sheet metal cut out to form desired characters, a sectional translucent partition positioned between said sign characters and the lamps and adapted to be supported by the second set of guides, the height

of the sign characters and the sections of the partitions being such as to permit them to be removed and inserted by telescoping the same within the upper guides, said sections and said sign characters being separately removable whereby access may be had to any point in the frame without removing all the sign characters and sections of the partition.

- 10 2. An illuminated sign comprising a box-like frame fitted interiorly with lamps, sets of horizontal guides formed at the top and bottom of the frame adjacent the front thereof, a plurality of independent sign characters adapted to be received by one of said sets of guides, a sectional translucent partition positioned between said sign characters and said lamps and adapted to be supported by the second set of guides, the height

of the sign characters and the sections of the partition being such as to permit them to be removed and inserted by telescoping the same within upper guides whereby said sections of the partition and said sign characters may be separately removed to permit 25 access to be had to any point in the frame without removing all of the sign characters and sections of the partition, said sign characters being formed of rectangular sheets of sheet metal cut out to form openings in the 30 shape of the desired characters, marginal edges of said openings being inwardly beveled and extending to a point in close proximity to said partition, and a hand hold fixed 35 on each of said sign characters and each of said sections of the partition.

TRACY W. SIMPSON.
